UNITED STATES PATENT OFFICE.

JOSEPH A. MANAHAN, OF NEW YORK, N. Y.

MOUTHPIECE OR STEM FOR SMOKERS' ARTICLES.

SPECIFICATION forming part of Letters Patent No. 757,760, dated April 19, 1904.

Application filed December 22, 1902. Serial No. 136,236. (No model.)

To all whom it may concern:

Be it known that I, JOSEPH A. MANAHAN, a citizen of the United States, residing in Manhattan borough, New York city, in the county 5 and State of New York, have invented new and useful Improvements in Mouthpieces or Stems for Smokers' Articles, of which the following is a specification.

This invention relates to certain improvements by which such an article as a pipe or holder for cigars, cigarettes, and the like is made to sit conveniently in the mouth or to the tongue of a smoker and a pleasant delivery of smoke is assured without liability of 10 moisture, nicotin, or objectionable matter entering the mouth.

This invention is set forth in the following specification and claims, and illustrated in the annexed drawings, in which—

Figure 1 shows a pipe embodying this invention and in use. Fig. 2 shows the mouthpiece. Fig. 3 is an end view of Fig. 1. Fig. 4 is a sectional plan view of the stem. Fig. 5 shows a modification. Fig. 6 is a plan view 20 of Fig. 5. Fig. 7 is a sectional view of a further modification. Fig. 8 is a side view of Fig. 7.

A stem E is shown with smoke channel or bore F. A pipe-bowl is shown at A; but by 30 the word "bowl" is included not merely a tobacco-receiver, as any funnel or suitably shaped receiving portion for a cigar or the like is included in the invention.

The bowl is shown with stem-section B, having channel C to lead smoke into the stem E. This channel C is shown slanting or inclined downwardly to a well or pocket portion D.

The mouthpiece or tip K has a stem-section 40 I, adapted to screw to or connect with the stem. This mouthpiece has the smoke-channel H and smoke hole or outlet J.

The tip or mouthpiece has a smoke-deflector L, the under part of which is curved to 45 serve as a rest for or position the tongue O of the smoker, the teeth N serving to hold the tip or pipe in the mouth or between lips M. The smoke-hole opens upwardly, and the smoke Q striking the deflector spreads from thence in the mouth. The channel H leads to or

terminates in a well G, adapted to catch juice, moisture, or the like and prevent the same reaching the mouth or the tongue. The well G can be formed by suitably depressing or enlarging bore F of the stem. Likewise the 55 well, formed as shown at D, forms a further safeguard against objectionable matter traveling along the stem.

The channel of the mouthpiece is shown of larger diameter than the channel or bore F 60 of the stem, and the mouthpiece-channel extends below the stem-channel, or, in other words, the stem-channel is located above the axis or along the upper part of the stem.

In Fig. 5 the outlet J is shown shortened 65 as compared with Fig. 1, the mouthpiece being of somewhat different shape.

In Figs. 7 and 8 the outlet J is shown forked or divided to cause a division or spreading of 70 the smoke.

It will be obvious from the foregoing description and upon an inspection of the drawings alluded to therein that the improved smoker's article includes a bowl provided with a stem-section having a smoke-channel, a stem 75 having a bore of differential diameter, the end portions of the bore being of greater diameter than the intermediate portion which constitutes a smoke-channel and being extended below the said intermediate portion to 80 constitute wells, the outer well serving to receive the stem-section, while the inner one receives a mouthpiece, both the mouthpiece and stem-section having smoke-channels. In the present instance the smoke-channel in the 85 stem-section opens directly into the interior of the bowl and leads downward and into the outer well at an angle, the result being that any objectionable matter that is in the pipe is conveyed into said well and will not pass 90 through the intermediate portion of the bore or smoke-channel. The inner well of course serves to receive any saliva that may be forced from the mouth, so that such saliva will not be forced into the bowl.

What I claim as new, and desire to secure by Letters Patent, is—

1. A smoker's article including a bowl provided with a stem-section having a smoke-channel, a stem having a bore wholly within 100

said stem and of differential diameter, the end portions of the bore being of greater diameter than the intermediate portion which constitutes a smoke-channel, and being extended below said intermediate portion to constitute wells, the outer well serving to receive said stem-section, and a mouthpiece fitted into the inner well, having a smoke-channel.

2. A smoker's article including a bowl provided with a stem-section having a smoke-channel, a stem having a bore wholly within said stem and of differential diameter, the end portions of the bore being of greater diameter than the intermediate portion which constitutes a smoke-channel, and being extended below said intermediate portion to constitute wells, the outer well serving to receive said stem-section, and a mouthpiece fitted into the inner well, having a smoke-channel, said smoke-channel having branches at its inner end.
3. A smoker's article including a bowl pro-

vided with a stem-section having a smoke-channel, a stem having a bore wholly within said stem and of differential diameter, the end portions of the bore being of greater diameter than the intermediate portion which constitutes a smoke-channel, and being extended below said intermediate portion to constitute wells, the outer well serving to receive said stem-section, and the smoke-channel in the latter opening directly into the interior of the bowl and extending downward therefrom at an angle and into said outer well, and a mouthpiece fitted into the inner well, having a smoke-channel.

In testimony whereof I have hereunto set my hand in the presence of two subscribing witnesses.

JOSEPH A. MANAHAN.
